ENVELOPE

Wesley P. Shomaker, Richmond, Va.

Application June 29, 1938, Serial No. 216,422

5 Claims. (Cl. 229—85)

My invention relates to improvements in envelopes, and to means for opening sealed envelopes; and it relates more particularly to those single and double envelopes in which offerings 5 in the form of coin, currency, or cheques are usually enclosed. When such envelopes are sealed by the old and usual means, it is a lengthy task to open a large number of them and to remove the contents. It would be a different matter to simply tear the envelope apart; but in many cases this would prolong rather than shorten the work, because, on the face and back of the envelope there are usually printed headings indicating the destination of the offering, quotations, and a numeral identifying the giver. It is most desirable therefore not to destroy the envelope until the offering has been extracted, and its destination and the number of the giver have been recorded.

20 Other envelopes have been designed with a similar object in view; but many have failed because of the cost of manufacture, or because the envelope had some feature which interfered with the perfection of the printing on the face and on the back of the envelope. Others have been unpopular because they have been no easier to open than is an envelope with an ordinary closure.

If the flap of an envelope is gummed and is held down to its very edge, it requires more or less time to insert a paper opener or a finger nail under the flap in order to raise it.

If the flap has a V-shaped outline, and the V be left ungummed, we then have either an insecure fastening; or the point of the flap is held down.

But the flap with a V outline is objectionable for the reason mentioned above. If a line of printing crosses the point of the flap the pressure of the type is much greater on the flap than it is on either side of the flap; and consequently the impression of the line of type is not uniform. This is the case whether the impression be made on the face or on the back of the envelope; because, at the V we have three thicknesses of paper, while on either side of the V we have two thicknesses of paper. Consequently, on whichever side of the envelope the type is impressed, the counteracting pressure of the paper stock is uneven. For this reason, as well as for the sake of economy in material, it is desirable that the outline of the flap be rectangular, and that the bottom or free edge of the flap be in line with and parallel to the lines of printing upon the envelope.

The objects of my invention are to provide an envelope which shall be useful; which shall be low in cost of manufacture; which shall be the same in outline and cut of paper for both the single and the double types of envelope; which

shall present an even surface for the printing; which shall be easily opened; and which can be rapidly opened, whether it be of the single or the double type.

These objects I attain in the envelope shown 5 in the drawing; in which—

Figure I shows the completed envelope, open; Figure II shows the same envelope, closed;

Figure III shows the envelope blank, cut and 10 gummed, before folding;

Figure IV shows the closed envelope about to be opened;

Figure V shows the envelope after it has been opened.

In Figure III the numeral 2 indicates the paper 15 blank which when folded will take the shape shown in Figure I (open) and in Figure II (closed). Assume that we are looking at the inside surfaces of the envelope; then 3 is the inside of the back of the envelope; 4 is the inside of the front of the envelope; 5 is the mouth flap; and 6, 6 are the end flaps, all of said flaps being integral with the front wall 4.

In the back of the envelope, 3, I cut a tab 7. This I do by means of a steel hollow punch having a cutting or punching edge 8 shaped as a semicircle, or in any other suitable form. The cut is short; barely more than a semicircle, the diameter of which is about eleven-sixteenths of an inch—more or less. The upper end of the 25 cut forming the tab is about on the line of the edge of the mouth flap when the envelope is closed; see Figure II. The portion of the back wall 3 immediately above the cut forms the base portion of the tab.

On the inside of the mouth flap I place a narrow strip, or a series of dots, of gum, 10.

On the inside of the back, 3, of the envelope, and at its two ends, I place narrow strips or dots of gum, 12, which, when the envelope is folded 40 and closed will be made to adhere to the end flaps 6, 6. If the envelope blank be now folded we shall produce a single envelope; that is, an envelope having a single pocket the full length of the envelope.

On the inside of the back of the envelope, and at the middle of its length, I place a short strip, or a dot, of gum, above the tab 7, indicated at 45 14; while below the tab 7, and adjacent thereto, I place a strip or dots of gum 16. On the tab 50 itself there is no gum. The gum at 14 and 16 is indicated by dotted lines in Figures I and II. The gum 14 and 16, and the tab 7 are in the medial line of the envelope extending from top to bottom as shown.

The difference between the single and the double envelopes is that in the former the gum at 14 and 16 is not used. In the case of a large order of single envelopes, this gum would not be used at 14 and 16 at all. But it is also possible 55 60

to place gum at 10, 12, 14, and 16; allow the gum to dry; and then at any time prepare single envelopes by folding and dampening only the gum at 12; or double envelopes by dampening the gum at 12, 14, and 16.

In some cases double envelopes are perforated—usually down their middle or central lines—so that the two halves may be torn apart and yet have two completely sealed envelopes. The perforations 18, Figures I and II, being made down the central line on which the adhesive is applied at 14 and 16; when the halves of the envelope are separated, the separated edges will still be sealed together; and each half will have a half 15 of the tab 7. The separation may be effected before or after opening. The tab 7, which is cut in the back wall of the envelope, is exposed below the edge of the flap 5 of the closed envelope, and normally lies in the same plane as the back 20 wall 3 to provide an even surface for printing. If the envelope be taken in hand, and it be bent, ever so slightly, along the line of its length (see Figure IV), the tab will rise from the back of the envelope; and it then be readily seized by the 25 finger and thumb of the other hand. A pull on the tab in a direction away from the bottom of the envelope will lift the entire flap 5; and at the same time the base portion of the tab will be torn from the back wall 3 of the envelope; though 30 it remains held to the flap 5 by the gum 10. Note that the tab 7 is just so wide, and consequently its adhesion to the gum 10 so strong, that when its base portion is torn from the back of the envelope and from the gum at 14, it remains attached to the flap 5. This re-opening of the envelope is shown in Figure V.

What I have said of the tab 7 remaining gummed to the inside of the flap 5 when the envelope is opened, is equally true of the half tab and half flap when the envelope is torn along the perforations 18 before the envelope is opened. Whether the envelope be a single pocket envelope or a double pocket envelope there is only one tab; and the operation of opening the envelope is the same in either case.

I claim:

1. An envelope including a front wall and a back wall, a flap integral with the front wall and adapted to be folded over the back wall to cover a portion thereof, a free tab cut from the back wall and so located therein as to be exposed for grasping when the flap occupies its above indicated covering position, said tab having a base portion integral with the back wall and so located as to be covered by the flap when the latter is in the aforesaid covering position, and adhesive means provided on the envelope and so located as to operate as a fastening means between the flap and the aforesaid base portion, whereby, when the flap is fastened to the said base portion, the flap may be freed from the back wall by grasping the free tab and tearing out its base portion from the back wall.

2. An envelope including a front wall and a back wall, a flap integral with the front wall and adapted to be folded over the back wall to cover a portion thereof, a free tab cut from the back wall and so located therein as to be exposed for grasping when the flap occupies its above indicated covering position, said tab normally lying in the same plane as the back wall whereby an even printing surface is presented but adapted to be projected from said plane for grasping by bending the envelope, said tab having a base

portion integral with the back wall and so located as to be covered by the flap when the latter is in the aforesaid covering position, and adhesive means provided on the envelope and so located as to operate as a fastening means between the flap and the aforesaid base portion, whereby, when the flap is fastened to the said base portion, the flap may be freed from the back wall by grasping the free tab and tearing out its base portion from the back wall.

3. An envelope including a front wall and a back wall, a flap integral with the front wall and adapted to be folded over the back wall to cover a portion thereof, a free tab cut from the back wall and so located therein as to be exposed for grasping when the flap occupies its above indicated covering position, said tab having a base portion integral with the back wall and so located as to be covered by the flap when the latter is in the aforesaid covering position, a spot of adhesive joining said base portion to the front wall on a medial line of the envelope extending through said tab, adhesive means joining portions of the front and back walls together on said medial line at a portion thereof adjacent to but spaced from said tab and on the opposite side of the tab from said spot of adhesive, and adhesive means provided on the envelope and so located as to operate as a fastening means between the flap and the aforesaid base portion, whereby, when the flap is fastened to the base portion, the flap may be freed from the back wall by grasping the tab and tearing out its base portion from the back wall.

4. An envelope including a front wall and a back wall, a flap integral with the front wall and adapted to be folded over the back wall to cover a portion thereof, a free tab cut from the back wall and so located therein as to be exposed for grasping when the flap occupies its above indicated covering position, said tab normally lying in the same plane as the back wall whereby an even printing surface is presented but adapted to be projected from said plane for grasping by bending the envelope, said tab having a base portion integral with the back wall and so located as to be covered by the flap when the latter is in the aforesaid covering position, a spot of adhesive joining said base portion to the front wall on a medial line of the envelope extending through said tab, adhesive means joining portions of the front and back walls together on said medial line at a portion thereof adjacent to but spaced from said tab and on the opposite side of the tab from said spot of adhesive, and adhesive provided on the envelope and so located as to operate as a fastening means between the flap and the aforesaid base portion, whereby, when the flap is fastened to the base portion, the flap may be freed from the back by grasping the tab and tearing out its base portion from the back wall.

5. In a quick-opening envelope having a closure flap on its front wall, foldable over the rear wall to close the opening of said envelope, a cut-out pulling tab in the body of said rear wall, below the free edge of said flap, the uncut portion of said rear wall adjacent said tab forming a securing web for said tab, said web being so located as to lie beneath said flap when the latter is closed, and a limited area of gumming on said flap substantially in line with said pulling tab, whereby when said tab is pulled upwardly, said flap will be pulled therewith to open the envelope.

WESLEY P. SHOMAKER.
